UNITED STATES PATENT OFFICE.

EDWIN W. WHITCOMB, OF CHICAGO, ILLINOIS, ASSIGNOR TO GEORGE D. WHITCOMB, OF SAME PLACE.

MINING-MACHINE.

SPECIFICATION forming part of Letters Patent No. 398,298, dated February 19, 1889.

Application filed August 10, 1888. Serial No. 282,471. (No model.)

To all whom it may concern:

Be it known that I, EDWIN W. WHITCOMB, a citizen of the United States, residing at Chicago, in the county of Cook and State of Illinois, have invented a certain new and useful Improvement in Mining-Machines, which is fully set forth in the following specification, reference being had to the accompanying drawings, in which—

10 Figure 1 is a plan view of a machine embodying my invention; Fig. 2, a plan view of the supporting-brackets detached from the machine; Fig. 3, a sectional view taken on the line 1 1 of Fig. 2; Fig. 4, a sectional view 15 taken on the line 2 2 of Fig. 2; Fig. 5, a sectional view taken on the line 3 3 of Fig. 2, and Fig. 6 a side elevation of the same detached.

Like letters refer to like parts in all the figures of the drawings.

20 My invention relates to mining-machines, and more particularly to that class shown in Letters Patent No. 335,328, granted February 12, 1886, to George D. Whitecomb, and in the 25 other Letters Patent therein enumerated.

My invention relates more particularly to the manner of mounting or supporting said machine, and has for its object to provide means for that purpose whereby the machine 30 will be rendered capable of use in a space of less height than heretofore and held up to its work more efficiently.

I will now proceed to describe a construction in which my invention is practically carried out in one form, and will then particularly point out in the claims those features 35 which I deem to be new and desire to protect by Letters Patent.

In the drawings, A represents the machine 40 proper, which I have shown as of the form shown and described in said Letters Patent No. 335,328, although my invention is of course adapted for use in conjunction with any machine of the same general type.

45 B represents the axle or stub journals, which, in these machines as heretofore constructed, receive the wheels which serve to support the machine. The wheels, being circular, of course extend as much above the 50 axle as below and materially increase the height of the machine at its forward portion.

This increase of height materially affects the capabilities of the machine for use in low cuttings by rendering it difficult or impossible to advance the machine as far as desirable 55 when the cuttings are low and contracted at the top. In order to obviate these disadvantages, I substitute for the wheels which have heretofore been employed brackets C, one for each side of the machine. These brackets are 60 approximately triangular in their general form, and are each provided at their upper end with a sleeve-bearing, c, adapted to fit snugly over the stub-axles B. The sleeves c are, however, sufficiently loose on the axles 65 to permit the sleeves to move freely thereon.

In order to hold the brackets C in line with each other and prevent independent movement of the two with respect to each other, they are connected by means of a transverse 70 rod or bar, D, the ends of which are reduced, as shown at d, the said reduced ends passing through and projecting beyond the brackets and being threaded to receive nuts d', by means of which the two brackets and the rod 75 D are rigidly connected. The rod D is pro-

vided at each end, just within the bracket, with a bearing portion, D', formed between the bracket and a collar, d', on the rod, and on the said bearing portions there are mounted 80 rollers E, which serve to support the bracket, said rollers projecting below the brackets and resting upon the ground or platform. At each end of each bracket there is located a roller, E',

85 preferably somewhat smaller than the rollers E, and secured to the bracket by means of a stub-axle, e, and nut e', as shown in Fig. 5. It will be observed that, these auxiliary rollers being, as just pointed out, of less di-

ameter than the main supporting-rollers, said 90 main supporting-rollers project downward below the auxiliary rollers, as shown more particularly in Figs. 4 and 5, and thereby permit the bracket to be tilted either backward or forward, as desired, upon the main supporting-rollers, so as to hold the machine up to its work in a more satisfactory manner.

In conjunction with each main supporting-roller E, I employ a brake, F, which is pivoted to the bracket C on the inner side thereof, and held normally away from the roller E by means of a spring, f. This brake is operated

by means of a rod, F', pivoted thereto at its forward end, its rear end being provided with a treadle or foot-rest, f', by means of which it may be operated.

5 It will be seen that by the use of the brackets just described a more compact supporting device is obtained, since nothing projects above the axles of the machine, which is therefore adapted to be used in more contracted spaces. The machine is free to tilt upon the brackets, and the brackets themselves are free to tilt upon the ground or platform upon which they rest. The supporting-rollers provide a ready means for moving 15 the machine forward or back, while at the same time they hold the machine up to its work better than the large wheels heretofore employed. The operator, by placing his feet upon the treadles or foot-rests f', may force 20 the brakes F against the main supporting-rollers E, when desired, and may thus prevent the recoil of the machine or lessen the same to any desired extent, and thus hold it up to its work.

25 It is obvious that various modifications in the details of construction may be made without departing from the principle of my invention, and I therefore do not wish to be understood as limiting myself strictly to the 30 precise details hereinbefore described, and shown in the drawings.

Having thus described my invention, what I claim as new, and desire to secure by Letters Patent, is—

1. The combination, with the mining-machine A and its central axle, B, of the brackets C, mounted loosely on said axle, and each provided with a central main supporting-roller, E, and with an auxiliary roller, E', at each end, said main roller projecting farther 40 downward than the auxiliary rollers, substantially as and for the purposes specified. 35

2. The combination, with the mining-machine A and its central axle, B, of the brackets C, mounted loosely on said axle, the transverse rod D, connecting said brackets, the main supporting-rollers E, mounted on said rod, and the auxiliary supporting-rollers E', mounted at the ends of each bracket, said supporting-rollers having their axes of revolution in the same plane, and the auxiliary rollers being of smaller diameter than the main supporting-rollers, substantially as and for the purposes specified. 45

3. The combination, with the mining-machine and its supporting brackets and rollers, of the brakes F, pivoted on the brackets, springs f for holding said brakes normally away from the rollers, and operating-rods F', provided with treadles or foot-rests f', substantially as and for the purposes specified. 55

EDWIN W. WHITCOMB.
